UNITED STATES PATENT OFFICE.

JOHN F. CARPMILL, OF NEW BRITAIN, CONNECTICUT, ASSIGNOR TO THE NORTH & JUDD MANUFACTURING COMPANY, OF NEW BRITAIN, CONNECTICUT, A CORPORATION OF CONNECTICUT.

BUCKLE.

Application filed December 6, 1921. Serial No. 520,302.

To all whom it may concern:

Be it known that JOHN F. CARPMILL, a citizen of the United States, residing at New Britain, in the county of Hartford and State 5 of Connecticut, has invented certain new and useful Improvements in Buckles, of which the following is a specification.

This invention relates to buckles. A buckle involving the invention may be obviously used in various ways. It may be employed with advantage for instance, for personal adornment, generally in connection with a belt; it can be utilized also in association with harness or with a strap such as 10 is used for holding articles like school books. These are three of many illustrations. A buckle of the same general type as that covered herein, usually comprises a body member and a clamping member. There is 15 one objection to the present type of buckle of this same general character, in that it has the inherent defect of not functioning properly to hold belts or webs which vary in thickness. Therefore one of the fundamental objects of the invention, is the provision of effective means by which the belt 20 can be securely held in clamping relation with the body, regardless of its thickness, naturally within the capacity of the buckle. The device possesses many other features of 25 novelty and advantage which with the foregoing will be set forth at length in the following description, wherein I will outline in detail several of the many forms of embodiment of the invention which I have selected 30 for illustration in the drawings accompanying and forming part of the present specification. Clearly I am not restricted to such disclosure. I may depart therefrom in many 35 respects within the scope of the invention defined by the claims following said description. While I have mentioned one of the fundamental objects of the invention I might also note that I can construct the 40 buckle in a relatively-inexpensive manner, that the same is simple in construction and is highly effective in action.

Referring to said drawings:

Figure 1 is a perspective view of a buckle 45 involving the invention.

Figs. 2 and 3 are similar views of the body member and the actuator.

Fig. 4 is a like view of the clamping member and the actuator connected, a portion of 50 the fixed part of the belt, showing.

Fig. 5 is a perspective view of the clamping member.

Fig. 6 is a sectional end elevation, the body member being shown in cross section.

Fig. 7 is a longitudinal section, the dotted 60 lines showing how two different size belts can be held.

Fig. 8 is a view corresponding to Fig. 7 of a slight modification.

Fig. 9 is a practically similar view of a 65 modification.

Fig. 10 is a practically similar view of a modification.

Fig. 11 is a practically similar view of a 70 modification.

Like characters refer to like parts throughout the several views.

The buckle involves a body member of some suitable kind. That shown is denoted in a general way by 2, and it is represented 75 as including in its make up the face portion 3 which is slightly longitudinally arched and generally made of some sheet metal. It has along opposite edges and co-extensive therewith the side flanges 4. The said side flanges 80 as illustrated are provided with inwardly projecting segmental lips 5 extending toward each other and located as shown, at about the front portion of the body member, the belt or its equivalent being usually 85 fixedly connected with the rear portion of the body member, although not directly. The said body member and the side flanges 4 thereof, are provided slightly to the rear of their centers, with the transversely-aligned 90 lugs or ears 6 having pivot perforations 6' which function as I will hereinafter set forth.

To hold the free end portion of the belt in firm relation with the body member 2, 95 a clamping member such as that denoted in a general way by 7 is shown. The clamping member 7 is also desirably made of sheet metal. It comprises a rounded cam-like body or web 8, the effective or binding portion of which is ribbed as at 9 to secure a better hold upon the belt. The ends 8' 100 of the cam-like body offstand perpendicularly and fit practically flatwise against the inner surfaces of portions of an actuator 105 hereinafter set forth, and are perforated as at 10, these perforations coinciding with the perforations 6' to which I have referred. The outer portion of the cam-like body 8 has a rearward extension 11, the length of 110

2
which is a trifle less than that of the cam-like body 8.

The clamping member 7 is movably mounted and the best effects are obtained by pivoting it in position. The pivot means may be of any suitable character, the pivot 12 being shown for the purpose. This pivot extends through the transversely alined perforations 6' and 10, and its ends exteriorly of the flanges 4 are usually headed. This is a way of properly movably mounting the clamping member being merely one of several for as will be inferred, the invention comprises certain fundamentally and broad relations. In Fig. 4 the pivot 12 is shown before its head, but in Fig. 1 where the parts are assembled, the heads at the ends of the pivot plainly show.

There is an actuator for the clamping member 7 and this actuator may be of any proper character. That shown and denoted in a general way by 13 answers my requirements. Said actuator as represented comprises a flat body 14 upon the forward edge of which is an eye 15 about midway of the transverse extent of the buckle and curled about the cross-bar 7' of the clamping member to thus flexibly connect the actuator with the clamping member. This flexible connection constitutes a proper actuating connection between the actuator 13 and the clamping member 7. In addition to the eye 15, said body has at its ends the inwardly extending ears 16 which are situated between the ends 8' of the clamping member 7 and the side flanges 4. These ears as shown, have slots or openings 17 and through the respective slots or openings 17, the pivot 12 freely extends.

The actuator 13 which also functions after the fashion as what is sometimes known as a "terminal member," has at its rear or back portion, the loop 18 through which the fixed end portion of the belt 19 may be extended and then stitched in place, which is merely one of several ways of fixedly connecting the belt or its equivalent with the actuator. This actuator as will be clearly understood has a multiple connection with the clamping member, there being as shown two such connections, one of them desirably free or loose which permits a relative motion between the actuator and the clamping member. As I have noted, there is a duplex connection between the actuator and the clamping member and while it is desirable that one of these connections be a loose one, I have, nevertheless, in the construction illustrated, shown both connections as loose. It will of course be clear that the buckle comprises a body member, and a clamping member movably mounted thereon, and means whereby the clamping member can be set into active relation solely or only by a rearward pull, this action be-

ing brought about through the pull of the belt upon the actuator and the construction is such that the belt can be firmly clamped regardless of its thickness. It will be clear that upon a pull on the free end 70 of the belt which is the right lower end thereof, the rear end of the belt, will be pulled and will thus pull the actuator 13 in a corresponding direction or toward the right in Fig. 7 and the actuator will rock 75 the clamping member on its axis and thus set the same firmly against the belt regardless of the thickness thereof. In Fig. 7, I have shown by dotted lines, a belt 19' and in the same view have shown also by dotted 80 lines the relation of the parts when the thinner belt is to be held.

In Figs. 8, 9, and 10, I show three of many modifications. The only difference in these views and in the construction shown in Figs. 85 1 to 7 inclusive is with regard to the loose joint between the clamping member and the actuator. In Fig. 8 the parts which are the same in construction as in the preceding views, will bear similar characters with the exponent "a." The actuator 13^a has the pendant ears 16^a having slots 17^a through which the pivot 12^a extends. In Fig. 9 the ears 16^b have slots 13^b elongated for the passage of the pivot 12^b. In Fig. 10 the ears 95 16^c have practically circular openings 17^c to loosely receive the pivot pin 12^c.

In Fig. 11 the actuator 13^d has at its rear portion, the ears 21 between which the end 100 of the belt 19^d may be held in fixed relation as by the clamping member 20 pivoted between the ears 21, against the body of the actuator 13^d.

In the several forms of the invention it will be clear that the buckle comprises a 105 body member, a clamping member movably supported by the body member, and an actuator for the clamping member, movably connected therewith and having also an independent actuating connection therewith. 110 Taking Fig. 4 for example which is more or less typical of the other views, the movable connection is made by means of the eye 15 and the bar 7 so that the actuating device 115 and the clamping member can operate relative to each other. The actuating or setting connection is made by means of the slot 17 and the pin 12. This independent actuating connection is also desirably a loose one, thus adapting the clamping member to co-operate 120 with belts which vary in thickness which is one of the vital features of the invention. Another important point is the fact that the setting of the clamping member, is effected solely by a backward or rearward pull thereon. 125 In the construction shown both of these highly advantageous features are present, but there may be instances where this is not the case.

The ears 16 have a loose connection by 130

means of a pin and elongated slot joint in the several views, although the ears in question carry exponent marks in several of said views. Referring in this connection to Figs.

5 1 to 7 inclusive, the ears 16 receive the pin 12 so that as the actuator 14 is swung over between the limits of action, the end walls of said slots 17 will engage the pin 12 to thus limit the motion of said actuator 14. It 10 should be noted that as the actuator 14 is swung from the position it is shown as occupying in Fig. 7, the walls of the slot 17, act against the pin 12, to thus set the clamping member 9.

15 What I claim is:

1. A buckle comprising a body member, a clamping member pivotally supported for rocking movement by the body member, and an actuator for the clamping member, pivotally connected therewith and provided with ears through which the pivot of the clamping member loosely extends.

2. A buckle comprising a body member, a cam clamping member pivotally supported for rocking movement by the body member, and an actuator for the clamping member pivotally connected therewith and provided with ears having openings through which the pivot of the clamping member

loosely extends, the actuator also having means for the connection therewith of a belt.

3. A buckle comprising a body member, a cam clamping member pivotally supported for rocking movement by the body member, and an actuator for the clamping member pivotally connected therewith and provided with ears having openings through which the pivot of the clamping member extends for rocking movement, the actuator also having means for the connection therewith of a belt.

4. A buckle comprising a body member, a cam clamping member pivotally supported for rocking movement by the body member, and an actuator for the clamping member loosely connected therewith and provided with ears having openings through which the pivot of the clamping member extends for rocking movement, the actuator also having means for the connection therewith of a belt.

In testimony whereof I affix my signature.

JOHN F. CARPMILL.

In presence of—

MARY F. LONG,
HEATH SUTHERLAND.
